Application February 21, 1946, Serial No. 649,450

12 Claims. (Cl. 189—26)

(Granted under the act of March 3, 1883, as
amended April 30, 1928; 370 O. G. 757)

1

The invention described herein may be manufactured and used by or for the Government for governmental purposes, without the payment to me of any royalty thereon.

The present invention relates to masts.

In the erection and use of various braced compression members, including masts or towers, particularly of the portable type, such as for radio antennas and the like, it is desirable that the parts have lightness coupled with sufficient structural strength to resist the stresses incident to erection and use. Although the present invention is particularly well adapted to portable radio towers and it will be illustrated in connection therewith, it is to be understood that the invention has considerably wider application.

Conventional portable masts and the like are usually sustained by a plurality of guys. In sustaining such masts great care must be taken during erection to avoid rupture of the central mast member. In many cases it has been found necessary to make the central mast member considerably oversized and overweight so that it may withstand the rigors of erection.

If a mast is of the portable type it is ordinarily desirable that it be separable into convenient units to facilitate transportation and handling. Difficulties have arisen in connection with providing suitable coupling means to join said units into an integral structure. Oversized, overweight and complicated parts are a handicap to portability.

The present invention is intended to provide means and a method of construction for masts and the like and also a means of erection wherein simple, relatively inexpensive parts, of less weight and smaller size, may be utilized for structures which may be separated into easily managed units, which may be simply and quickly erected, and which have sufficient structural strength and stability to provide the desired safety factors.

It is therefore an object of the present invention to provide a mast or other structure which may be fabricated of lightweight materials, such as aluminum.

It is a further object to provide such a mast which may be assembled of a plurality of units, each of which may be of a size and weight suitable for portability.

It is still another object to provide simple means for giving such a mast sufficient structural strength to allow it to be easily and safely erected and to enable it to withstand windage, loads and other stresses involved in its use.

It is a further object to provide means for prestressing the elements of a mast so as to give it the requisite structural strength and stability.

It is still another object to provide means for applying tension to brace members without the use of turnbuckles or the like thereon.

Yet another object is to provide a means for erecting a mast which is both simple and safe.

2

It is still another object to provide a construction for masts and the like which requires a much smaller number of guys and anchor means than conventional structures.

6 It is still another object to provide a mast wherein stresses within the parts are far better equalized than in conventional structures utilizing a plurality of sets of guys fastened at different levels.

10 It is another object to provide a construction for masts and the like which is triangular in cross section and thereby has greater sturdiness, strength and stability than conventional quadrilateral structures.

15 It is yet another object to provide a mast and the like wherein erection may be accomplished without the use of auxiliary gin pole devices.

The foregoing objects and others, which will become clear from the present specification, are 20 accomplished by providing a structure for a mast or the like which includes a central post, which may be made up of a single post or a plurality of post sections spliced together. Said mast is given rigidity and strength by means of a plurality (preferably three) of brace members which are secured, at their opposite ends, to the post and are forced outwardly, at their central portions, so as to be put under suitable tension, by means of strut members. Said strut members 25 are made adjustable in effective length in a manner somewhat similar to a conventional umbrella.

Each strut member incorporates a stiff strut having its outer end pivoted to the central portion of a brace member and having its inner end pivoted to a part (hereinafter referred to as a "spider") which is longitudinally slidable along the post and is provided with means to pivotally connect with the inner end of said strut. During 30 assembly of the components the said strut is disposed at an angle of somewhat less than 90° to the post. When the spider is moved longitudinally relative to the post, said angle approaches 90° thus pushing the central portion of 35 the brace member outwardly. This subjects the braces to tension and the post to compression.

A simple tower (as shown in Figures 1-4 and 8) might include a two section post provided with three outwardly extending adjustable struts and 40 suitable braces. The same principle might be applied to larger masts having any number of sections. One such tower made up of four post sections is shown in the accompanying drawings (Figures 5-7).

45 Said masts are preferably assembled on their sides on the ground and may then be raised in a number of ways. A simple erecting method, in which some of the parts needed for erection are incorporated permanently into the mast is 50 illustrated in connection with the simple tower aforesaid (Figure 4).

For a better understanding of the invention, together with other and further objects thereof,

3

reference is had to the following description taken in connection with the accompanying drawings, wherein like parts are indicated by like reference numerals and its scope will be pointed out in the accompanying claims.

In the drawings,

Figure 1 is an isometric view of a simple form of mast embodying the present invention;

Figure 2 is an enlarged fragmentary perspective view showing details of the central portion of the mast of Figure 1;

Figure 3 is a further enlarged fragmentary view of the central portion of the mast of Figure 1, the upper portion being shown in vertical section and the lower portion in elevation with parts cut away for clarity;

Figure 4 is an elevational view of the mast of Figure 1 during erection, the mast being shown in solid lines upon the ground and in broken lines when about halfway up;

Figure 5 is an elevational view of a more complicated mast incorporating the present invention;

Figure 6 is a fragmentary enlarged elevational view of the central portion of the mast of Figure 5.

Figure 7 is a plan view showing only the strut system at the central portion of the mast of Figure 5 and

Figure 8 is an enlarged perspective view of the lower post section and associated parts of the mast of Figure 1, portions being broken away and cross sectioned for clarity.

Referring now to the drawings, and more particularly to Figures 1-3 and 8 thereof, the form of radio antenna mast embodying the present invention which is there shown includes a central post sustained upon a base 11. Said central post is made up of lower and upper post sections 13, 15, each of which sections comprises an elongated metal pipe 17, having three longitudinally disposed slots 19 cut through it, 120° apart, at one end. The slotted end of each pipe 17 (namely, the upper end of the lower post section 13 and the lower end of the upper post section 15) is closed by a transversely disposed triangular end plate 21, which is pierced by a hole 23 at its midpoint and an inwardly extending slot at each corner, and which is rigidly secured to the end of the pipe by any suitable means, such as welding.

Three pairs of spaced parallel gusset flanges 25 (Figures 2, 3 and 8) are secured, as by welding, to the outside of each pipe 17, so as to extend outwardly from said pipe along both sides of each of the slots 19 aforesaid. Each of the flanges 25 is pierced along its length by several holes 27. The lower and upper post sections 13, 15 are aligned with each other, but with their end plates 21 spaced from each other, and are joined together by three splice plates 29, each of which is a flat elongated plate pierced by a hole at each end. Each splice plate 29 has one end extending between one pair of gusset flanges 25 of one of the post sections 13, 15 and bolted thereto by a bolt 30, and its other end similarly bolted to the other of said post sections.

Each pipe 17 is also provided with a spider 31 (Figures 2, 3 and 8). Each spider 31 is made up of a short internally threaded sleeve 33 to the outside of which are secured three radially disposed legs 35. Said legs 35 are rigidly joined to the sleeve 33, as by welding, and are positioned 120° apart and each leg is pierced by a pair of holes 39. A short tubular guide 37, positioned coaxially with the sleeve 33, is secured to the three

4

legs 35. Each spider 31 is positioned coaxially with one of the pipes 17 so that the sleeve 33 and guide 37 are positioned within said pipe and the three legs 35 extend outwardly through the slots 19 in said pipe. The tubular guide 37 is of a size to make a longitudinally slidable fit within the pipe 17.

Extending through the hole 23 in the end plate 21 and threaded into the sleeve 33 is a hexagonally headed spider adjusting bolt 41. Between the head of the bolt 41 and said end plate 21 is a suitable annular thrust bearing 40, which may be of the "Oelite" type, which is made up of metal impregnated with a lubricant. A collar 43 encircling the bolt 41 just inside the end plate 21 is fastened to said bolt by a cotter pin 42.

The heads of the two spider adjusting bolts 41 are provided, respectively, with an axially disposed dowel 45 and with an axial cavity 47, receivable to said dowel 45, so that said bolts may be positioned coaxially head to head for individual operational rotation. It will now be seen that, upon rotation of either one of the spider adjusting bolts 41, the spider 31, in threaded engagement with it, is caused to move longitudinally relative to the pipe 17.

The lower extremity of the lower post section 13 and the upper extremity of the upper post section 15 are each fitted with three pairs of outwardly extending spaced parallel gusset plates 49 which are respectively aligned with the pairs of gusset flanges 25 at the other ends of said post sections. The lower end of the lower post section 13 is rigidly joined to the T-shaped base 11 by means of a base bracket 53.

The T-shaped base 11 is made up of a stem 55 and a cross member 57, both of which are preferably made of metal pipe, one end of the stem 55 being securely joined perpendicularly to the cross member 57 at its midpoint, by any suitable means, such as welding, or preferably by a suitable separable bracket (not shown) to allow said stem 55 and cross member 57 to be disconnected for transportation. A pair of short tubular cross member extensions 58 are rotatably coaxially joined to the extremities respectively of the cross member 57 by means of pipes 60 of slightly smaller diameter, which are rigidly secured to said cross member extensions 58 and are rotatable relative to the cross member 57.

The stem 55, near its outer end, and each of said cross member extensions 58 is pierced by a transverse anchor opening 64 receivable to the upper end of a ground anchor 62 of any suitable type. A pulley 66 is secured (either permanently or removably) to the bitter outer end of the stem 55, for rotation about a horizontal axis.

The parts making up the base 11 are of such sizes that the three anchor openings 64 define the corners of an equilateral triangle. Extending upwardly from the stem 55 near its outer end and from each extremity of the cross member 57 is an erection connector arm 59, the purpose of which arms will be explained below.

A spider strut 61, preferably made of a length of metal pipe, is pivotally secured to the outer end of each of the six legs 35 of the two spiders 31, thus providing three pairs of spider struts 61 extending outwardly from the midportion of the central post, said pairs of spider struts 61 being spaced at 120° intervals about the central post. The outer ends of each pair of spider struts 61 are pivotably fastened to a strut connector 63.

Each of the three strut connectors 63 (see Figure 2) includes a horizontally disposed, flat strut gusset plate 65 to which are welded verti-

cally disposed upwardly and downwardly extending connector fins 67, each of which fins is pierced by a hole. Two gusset shackles 69 are secured respectively to said connector fins 67.

Each gusset shackle 69 is made up of a piece of flat metal folded upon itself so as to give it the shape of a U in cross section and its opposite sides are pierced by four holes in mutual register, one of said holes being a horizontally disposed slot 70. Each gusset shackle 69 is also pierced by an elongated fin aperture along its folded portion to allow one of the connector fins 67 to extend therethrough so as to be bolted to said gusset shackle by means of a bolt 71 passing through the slots 70. Said fin apertures are longer than the width of the connector fins 67 extending through them, to allow adjustment therebetween, as will be made clear hereinbelow. One of the strut connectors 63 is fitted, either permanently or temporarily during erection, with a metal ring 68. Said ring 68 should be to the same side of the post sections 13, 15 as the pulley 66 mentioned above. The three strut connectors 63 are joined by three struts 73 which form an equilateral triangle and maintain the strut connectors 63 in their equally spaced positions. Each strut 73 is preferably made of metal pipe, and each of its ends is slotted and bolted directly to one of the strut gusset plates 65.

Three lower braces 75, also preferably made of metal pipe, are bolted, at their lower ends, respectively to the gusset plates 49 at the lower end of the lower post section 13 and, at their upper ends, respectively to the three lower gusset shackles 69 of the three strut connectors 63. Three similar upper braces 77 have their upper and lower ends similarly bolted respectively to the gusset plates 49 at the upper end of the upper post section 15 and to the upper gusset shackles 69 of the strut connectors 63.

Three guys 79, which are also preferably made of metal pipe, have their upper ends pivotally secured respectively to the lower gusset shackles 69 of the strut connectors 63 and their lower ends secured respectively pivotably to guy bolts 81 which extend downwardly through holes in the upper ends of the erection connector arms 59 and are connected thereto (during erection of the mast) by adjusting nuts. The lower ends of said guy bolts 81, (when the mast is in its erected position) are secured respectively to three ground anchors 62 through suitable adjustable members, such as turnbuckles 83.

A radio antenna 85 (indicated by broken lines) may be sustained upon the upper end of the upper post section 15 in any suitable way and may be maintained thereon by three antenna braces 87 (also indicated by broken lines), preferably of metal pipe, secured at their upper ends to said antenna and at their lower ends respectively to the upper gusset shackles 69 of the strut connectors 63.

As shown in Figure 4, in order to erect the antenna mast described above (Figures 1-3 and 8) some additional equipment is necessary. This additional equipment includes a conventional chain hoist 89 which includes a loop 91 of chain by which it is operated and two single ends 93, 95, one of which is shortened while the other is lengthened upon operation of the said loop 91. Also required are a large coil spring 97 and an auxiliary ground anchor 62a which is used only during erection and is not needed to support the mast after erection.

The mast just described (Figures 1-4) may be raised in various ways. However, a preferred

erection method, and a method for which certain components of the mast were specifically designed, will now be described in connection with Figure 4.

The base 11 is first placed horizontally upon the ground in the position it is to occupy when the tower is erected. Using said base as a template a marker is placed in the ground below each anchor hole 64. The base 11 is then removed and three ground anchors 62 are sunk into the ground at the three places so marked. The base 11 is then replaced in the position which it will finally occupy, so that the three ground anchors 62 respectively extend upward through the three anchor openings 64.

The fourth auxiliary ground anchor 62a is then sunk into the ground at a point aligned with the base stem 55 and distant from the cross member 57 a distance equal to approximately one-half of the height of the finished tower, so that the three anchors 62 and the auxiliary anchor 62a will delineate the four extremities of a cross upon the ground.

The upper and lower post sections 13, 15, while on the ground, are then positioned end to end so that the dowel 45 on the head of one of the spider adjusting bolts 41 fits into the axial cavity 47 in the head of the other spider adjusting bolt 41. The three splice plates 29 are then slipped into the openings between the flanges 25 of the lower and upper post sections 13, 15. The opposite ends of said three splice plates 29 are then bolted respectively to the three pairs of flanges 25 of the lower and upper post sections 13, 15. The outer end of the base stem 55 is then swung upwardly, the cross member 57 pivoting about its axis during this operation, until the base 11 takes the position shown in Figure 4. The lower end of the lower post section 13 is then raised to the position shown in Figure 4 and secured to the base 11 by means of the base bracket 53.

The spiders 31 should be so positioned at this time that the legs of the upper spider are in register with the uppermost hole of the flanges 25 of the upper post section 15, and the legs 35 of the lower spider 31 are in register with the lowermost holes of the flanges 25 of the lower post section 13. The six struts 61 are then bolted to the outermost holes 39 of the six spider legs 31 and the other ends of said struts are bolted respectively to the six gusset shackles 69 of the three strut connectors 63. The lower and upper braces 75, 77 are then bolted into place between the strut connectors 63 and the gusset plates 49 and the guys 79 are bolted to the strut connectors 63 at one end and to the erection connector arms 59 at the other.

The spider bolts 41 are now rotated by means of a wrench so as to bring the spiders 31 toward each other. While this is being done the bolts 71 must be loose so that the gusset shackles 69 can slide outwardly while the strut gusset plates 65 and their connector fins 67 remain stationary. When the arms 35 of the two spiders 31 are so positioned that the inner holes 39 thereof are in register with the middle holes 27 of the flanges 25, they are bolted in place. The bolts 71 may then be tightened to secure the strut gusset plates 65 respectively to their upper and lower gusset shackles 69.

The chain hoist 89 is now attached to the ring 68 which is attached to the uppermost strut connector 63 as the mast rests on its side. The free end 93 of the said hoist 89 is brought over

the pulley 66 and down to the ground anchor 62 (to the right in Figure 4) where it is made fast. The other end 95 of said chain hoist 89 is connected to the spring 97, the other end of which is made fast to the auxiliary ground anchor 62a. The loop 91 of the hoist 89 is now pulled in the direction which will shorten the end 93 and lengthen the end 95. As this is done, the upper end of the mast will begin to rise and the entire mast structure will pivot about the axis of the cross member 57, said cross member rotating about the pipes 60.

When the mast has been swung up to a suitable working level, the antenna 85 and antenna braces 79 may be secured in place, whereupon the erection of the mast by means of the chain hoist 89 may be resumed until the post sections 13, 15 are vertical. The anchor 62 (to the right in Figure 4) will then have passed through the anchor opening 64 in the stem 55.

It will be noted that during erection the lower ends of the guys 79 are held in place by the erection connector arms 59. As soon as the mast is erect, however, the guy bolts 81 are secured to the anchors 62 through the turnbuckles 83 and are suitably tensioned thereby. The arms 59 may then either be left in place or removed, as desired, as they are only needed during erection or dismantling of the mast. The chain hoist 89, spring 97 and auxiliary anchor 62a (to the left in Figure 4) may also be removed.

It will be seen that the tightening of the spiders 31, as described above, will cause suitable tension of the braces 75, 77 and compression of the pipes 17, but will subject the struts 73 to no strain at all as the strut gusset plates 65, to which they are secured, are not moved outwardly during the prestressing operation.

The mast described (Figures 1-4 and 8) may be sustained by but three guys 79 and ground anchors 62, whereas comparable masts of conventional design are rectangular so as to require at least four guys and four anchors and more likely require a multiple of four guys and anchors, said guys going up to steady the masts at different levels. For example, a conventional mast known to the applicant requires sixteen guys and anchors, and two auxiliary anchors needed during erection, making eighteen anchors in all, whereas a mast embodying the present invention, of like size and usefulness, requires but three anchors, and one auxiliary anchor for erection, making four in all. Thus there is a great saving in expense and labor. Also additional erection equipment, comprising gin poles and the like, are needed to raise a conventional mast whereas it may be dispensed with in erecting the mast described above.

A modified form of antenna mast embodying the present invention is shown in Figures 5-7. Said mast is constructed so as to utilize the same principles as in the simple mast already described, but is preferably used in a mast of larger size or in a mast of similar size but wherein smaller component parts are provided to facilitate portability.

Said modified form of mast is made up of a central post comprising four post sections 101, 102, 103, 104, which are similar to the post sections 13, 15 already described in connection with the simple mast (Figures 1-3), except that the intermediate post sections 102, 103 are provided with slots 19 and spiders 31 at both ends. The two lower post sections 101 and 102 are spliced together and are provided at their junction with

a strut system as already described and shown in connection with the simple form of mast (Figures 1-3 and 8). Thus said post sections 101, 102 are joined by three splice plates 29 and their strut spiders 31 are joined to three strut connectors 63 by means of six spider struts 61. The two upper post sections 103, 104 are also joined to each other in exactly the same way.

The two intermediate post sections 102, 103 however, although joined together by similar splice plates 29, are provided with a more complicated strut system (see Figures 6 and 7). Said strut system includes three inner strut connectors 105 and three outer strut connectors 107. Each inner strut connector 105 comprises an inner strut gusset plate 109 and upper and lower inner gusset shackles 113.

The inner strut gusset plate 109 is a flat horizontally disposed plate provided with upwardly and downwardly extending flat connector fins 111 and also pierced by two holes on each side receivable to the inner struts 115 and the intermediate struts 117. Each of the inner gusset shackles 113 is U-shaped in cross section, the arms being pierced by four holes in register, one of which holes is a horizontally disposed slot 119 for slidable coupling to a connector fin 111. Each shackle 113 is also pierced along its folded portion by an elongated fin aperture to slidably receive one of the connector fins 111.

The inner strut connectors 105 are pivotally joined respectively to the legs 35 of the spiders 31 by pairs of spider struts 61 as already described above in connection with the simpler tower (Figures 1-3 and 8).

Each inner strut connector 105 is rigidly joined to one of the outer strut connectors 107 by means of a pair of horizontally disposed extension struts 121. Each extension strut is preferably a length of metal pipe rigidly secured at one end to one of the inner gusset shackles 113 and at the other end to an outer gusset shackle 123. Each of the outer gusset shackles 123 is U-shaped in cross section, is pierced along its folded portion by an elongated fin aperture, and its arms are pierced by five holes in register, one of which holes is a slot 125, by which said shackle 123 may be slidably joined to an outer strut gusset plate 121, which is a horizontally disposed flat metal plate pierced by two holes and provided with two upwardly extending flat connector fins 129 extending into said shackles 123 through said elongated fin apertures in said shackles 123.

The three outer strut connectors 107 are rigidly joined to each other by three outer struts 131 which form a horizontally disposed equilateral triangle. Each outer strut 131 is provided at its midpoint with an intermediate strut connector 133 to which are rigidly connected the outer ends of the intermediate struts 117.

It will now be seen that, although the strut system (Figures 6 and 7) just described has more component parts than the simpler strut system described previously, the principle of operation is exactly the same.

When the various component parts of the mast (of Figure 5) have been joined together while on the ground, the spider bolts 41 at the several junctions between the post sections 101, 102, 103 and 104 are rotated to bring the pairs of spiders 31 toward each other. The lower junction (between post sections 101 and 102) and the upper junction (between post sections 103 and 104) will operate exactly as described in connection with the simple mast (Figures 1-3 and 8).

At the midjunction (between post sections 102 and 103) the adjustment of the two strut spiders 31, however, will cause the two inner gusset shackles 113 of each inner strut connector 105 to move outwardly. The inner strut gusset plate 109 however will not move, being only loosely connected to the gusset shackles 113 during this operation. The outward movement of the said inner gusset shackles 113 will likewise cause outward movement of the extension struts 121, rigidly secured thereto, and of the outer gusset shackles 123, rigidly secured to said extension struts 121. The outer strut gusset plate 127 during this operation will also be loosely connected and hence will not move outwardly. After the spiders 31 have been bolted into their stressed positions (as shown in Figure 6) the bolts joining the connector fins 111, of the inner strut gusset plates 109, to the inner gusset shackles 113, and the bolts joining the connector fins 129, of the outer strut gusset plates 127, to the outer gusset shackles 123 will be tightened.

The three outer strut connectors 107 are joined to the three upper strut connectors 63 by three upper outer braces 135 and said outer strut connectors 107 are similarly joined to the three lower strut connectors 63 by three lower outer braces 137.

The lower end of the lowermost post section 101 is joined to a base 139 by means of a ball and socket joint 141. Said base 139 is concave on its under surface and is provided with sharp downwardly extending feet 143.

The mast (Figure 5) is supported by three guys 145 which are preferably made of metal pipe and extend respectively from the three outer strut connectors 107 to three ground anchors 147 secured in the ground equidistant from each other.

As shown in the drawings (Figure 5) the mast supports an antenna 85 by means of an extension post 151 rigidly secured to the upper end of the uppermost post section 104. Said extension post 151 and antenna 85 are sustained by three antenna braces 153 which respectively are secured at their lower ends to the upper strut connectors 63 and are strengthened by three nonadjustable flat metal antenna struts 155 which extend outwardly from the lower end of the extension post 151 and are rigidly secured to said post and to the antenna braces 153.

The modified and more complicated form of the antenna just described (Figures 5-7) may be raised in any suitable manner. If it is to be raised as is the simpler form already described (Figure 4), it should preferably be provided with the T-shaped base 11 (as shown in Figure 1).

While there has been described what is at present considered preferred embodiments of the invention, it will be obvious to those skilled in the art that various changes and modifications may be made therein without departing from the invention, and it is, therefore, aimed in the appended claims, to cover all such changes and modifications as fall within the true spirit and scope of the invention.

What is claimed is:

1. In a mast, a vertically disposed central post, a strut system for said post including a spider longitudinally adjustable relative to said post and a stiff spider strut disposed obliquely to said post and pivotably secured at its inner end to said spider, means to adjust said spider longitudinally relative to said post, an upper brace secured at its lower end to the outer end of said spider strut and secured at its upper end to the

central post at a point higher than said strut system, and a lower brace secured at its upper end to the outer end of said spider strut and secured at its lower end to the central post at a point lower than said strut system.

2. In a mast, a vertical central post, a pair of strut spiders substantially concentric with said post and longitudinally adjustable relative thereto, each spider including a like plurality of legs extending substantially radially outwardly relative to said post, the legs of the spiders being disposed in pairs, each pair comprising a leg on the lower spider and a leg on the upper spider positioned substantially above it, means to adjust said spiders longitudinally relative to said post, a plurality of spider struts pivotably secured at their inner ends to said legs respectively so as to make up a plurality of pairs of spider struts, each pair comprising one spider strut substantially above another, a strut connector secured to the outer ends of the spider struts of each pair, a plurality of pairs of braces, each pair comprising a brace secured at its lower end to a strut connector and at its upper end to the central post at a higher level and a brace secured at its upper end to said strut connector and at its lower end to the central post at a lower level, each of said strut connectors including a strut gusset plate horizontally adjustable relative to the balance of said connector, and a plurality of struts joining the several strut gusset plates.

3. In a mast as defined in claim 2, a plurality of ground anchors disposed about the lower end of the central post and a plurality of guys connecting the several strut connectors to the several anchors.

4. In a mast, a vertical central post, a pair of strut spiders substantially concentric with said post and longitudinally adjustable relative thereto, each spider including a like plurality of legs extending substantially radially outwardly relative to said post, the legs of the spiders being disposed in pairs, each pair comprising a leg on the lower spider and a leg on the upper spider positioned substantially above it, a plurality of spider struts pivotably secured at their inner ends to said legs respectively so as to make up a plurality of pairs of spider struts, each pair comprising one spider strut substantially above another, a plurality of strut connectors, each strut connector comprising a horizontal strut gusset plate and two gusset shackles slidably secured to said plate respectively above and below it, said two gusset shackles respectively being pivotably secured to the outer ends of the spider struts of one pair thereof, a plurality of pairs of braces, each pair comprising a brace secured at its lower end to the upper gusset shackle of a strut connector and at its upper end to the central post at a higher level and a brace secured at its upper end to the lower gusset shackle of said strut connector and at its lower end to the central post at a lower level, and a plurality of struts joining the several strut gusset plates.

5. In a mast, a vertical tubular central post, two strut spiders adjustable longitudinally relative to said post, each strut spider comprising a central internally threaded sleeve longitudinally movable within said post and a plurality of outwardly extending legs, said legs respectively extending through longitudinal slots in said central post, a plurality of outwardly extending stiff spider struts respectively pivotably secured to said legs, said spider struts being disposed in pairs one above the other, the outer ends of the spider

struts of each such pair being pivotably secured respectively to a pair of gusset shackles, means for joining said gusset shackles of each pair, a brace joining the upper gusset shackle of each pair to the central post at a higher level, a brace joining the lower gusset shackle of each pair to the central post at a lower level, means to move the spiders longitudinally relative to the central post so as to move the gusset shackles outwardly from the post.

6. A mast as defined in claim 5, including struts connecting the several pairs of gusset shackles, the connections between the struts and shackles being slidable.

7. In a mast, a central post, a strut spider longitudinally adjustable relative to said post, an elongated brace member having its opposite ends secured to the post at two points spaced from each other, a stiff spider strut extending obliquely outwardly from said post and pivotably secured at its outer end to the brace member at a point intermediate the ends of said brace member and pivotably secured at its inner end to the strut spider, whereby the spider may be adjusted to swing said spider strut and thereby increase the perpendicular distance from the post to the outer end of said spider strut and thereby subject the brace member to tension and the post to compression.

8. In a mast, a central post, a strut spider longitudinally adjustable relative to said post, a plurality of elongated brace members having their opposite ends secured to the post at two points spaced from each other, a plurality of stiff spider struts extending obliquely outwardly from said post and pivotably secured at the outer ends respectively to the brace members at points intermediate the ends of said brace members and pivotably secured at their inner ends to the strut spider, whereupon the spider may be adjusted to swing said spider struts and thereby increase the perpendicular distances from the post to the outer ends of said spider struts and thereby subject the brace members to tension and the post to compression.

9. In a mast, a vertical central post, three strut spiders longitudinally adjustable relative to said post, said spiders including a central spider disposed substantially at the central portion of said post, a lower spider disposed intermediate the lower end of said post and the central portion thereof, and an upper spider disposed intermediate the central portion of said post and the upper end thereof, a plurality of lower elongated brace members having their opposite ends secured respectively to the lower end of the post and to the central portion of the post, a plurality of upper elongated brace members having their opposite ends secured respectively to the central portion of the post and to the upper end of the post, a plurality of stiff lower spider struts pivotably secured at their inner ends to the lower spider and at their outer ends respectively to the lower brace members at points intermediate the ends of said lower brace members, a plurality of stiff upper spider struts pivotably secured at their inner ends to the upper spider and at their outer ends respectively to the upper brace members at points intermediate the ends of said upper brace members, a plurality of central elongated brace members having their opposite ends secured respectively to the outer ends of the lower spider struts and the outer ends of the upper spider struts, and a plurality of stiff central spider struts

pivotably secured at their inner ends to the central spider and at their outer ends respectively secured to the central brace members at points intermediate the ends of said central brace members.

10. In a mast as defined in claim 9 which includes a plurality of ground anchors and a plurality of guys extending from the said ground anchors up to the central brace members at points intermediate the ends of said central brace members.

11. The method of erecting a mast, of the type having a central post and three struts extending outward from the midportion of the post and a three cornered base having pulley means at one corner and rotatable means at the other two corners to allow rotation of the mast about an axis extending through said other two corners, comprising the following steps: installing three ground anchors in the ground substantially at the points where the three corners of the base are to rest when the mast is erected, installing an auxiliary ground anchor at a point so that the four anchors delineate the extremities of a cross, the distance between the said auxiliary anchor and the nearest of the other anchors being less than the distance between the base and struts of the mast, assembling the components of the mast upon the ground so that the two corners of the base provided with rotatable means are disposed at two of the anchors and the struts are adjacent a point above said auxiliary anchor and the pulley means is on the corner of the base extending upwardly, securing a chain hoist to the outer end of the upwardly extending strut, running one free end of cable of said hoist over the pulley and down to the third ground anchor and securing it thereto, securing the other free end of cable of said hoist to a coil spring, securing the other end of said spring to the auxiliary anchor, and operating the chain hoist so as to pull in the first free end of cable thereof and let out the other end.

12. In a mast, a vertical central post, a strut extending obliquely, outwardly from said post, a brace extending from the outer end of said strut up to the post, a second brace extending from the outer end of said strut down to said post, means to swing said strut toward a more nearly horizontal position so as to lengthen the horizontal component of said strut and thereby subject said post to compression and prestress said braces, said means including a spider longitudinally movable relative to the post, the inner end of the strut being pivotably secured to said spider, and means to move said spider longitudinally relative to said post.

ERIC A. BLACK.
